UNITED STATES PATENT OFFICE.

ALBIN GARRETT AND RUFUS THOMAS, OF PHILADELPHIA, PENNSYLVANIA,
ASSIGNORS TO THE NATIONAL SEWING MACHINE COMPANY, (LIMITED,),
OF SAME PLACE.

TRIMMING ATTACHMENT FOR SEWING-MACHINES.

SPECIFICATION forming part of Letters Patent No. 242,296, dated May 31, 1881.

Application filed November 22, 1880. (No model.)

To all whom it may concern:

Be it known that we, ALBIN GARRETT and RUFUS THOMAS, citizens of the United States, residing in Philadelphia, Pennsylvania, have 5 invented certain Improvements in Sewing-Machine Attachments, of which the following is a specification.

Our invention relates to improvements in the shears connected with sewing-machines for the purpose of trimming the edges of the fabric simultaneously with the stitching of the same; and the objects of our improvements are, first, to afford facilities for the accurate adjustment of the vibrating blade of the shears, 15 and, second, to allow the fabric to pass freely onto the cutting-edge of the lower blade.

In the accompanying drawings, Figure 1 is a plan view of a sewing-machine from which part of the structure has been removed to illustrate our invention; Fig. 2, a perspective view of the shears and devices through the medium of which one of the blades is operated from a crank-pin on the driving-wheel of the machine; Fig. 3, a transverse section on the line 1 2, Fig. 1; Fig. 4, a detached perspective view of the fixed blade of the shears; Fig. 5, a view of the pivot for the upper blade; Fig. 6, a detached view of the recessed work-plate, drawn to an enlarged scale; and Fig. 7, a sectional view, also enlarged, and showing the relation of the fixed blade of the shears to said recessed work-plate.

As far as the sewing-machine itself is concerned, it may be similar to any of the machines in common use, and is provided with the usual needle-bar, presser-foot, and feed mechanism.

To the bed-plate A of the machine is secured a plate, G, made longitudinally and laterally adjustable, preferably by elongated slots, 40 through which set-screws less in diameter than the width of the slot pass into the bed-plate.

From the adjustable plate G projects the lower blade, h, of the shears, the upper blade consisting of the short arm i of a lever, H, 45 which is pivoted at x to the plate G, and the long arm of which has a slot to receive and guide the sliding block F, through which passes a portion of the pin K, Fig. 5, the other portion of the pin passing through an elongated

slot in an arm, M, and being secured thereto 50 by a nut, so that the pin can be adjusted on the arm to any extent which the desired position of the upper blade of the shears may demand. The arm M is secured to one end of a shaft, N, which has its bearings in suitable 55 boxes or lugs on the under side of the bed-plate A, and on the opposite end of the shaft is an arm, P, connected, by a link, T, to a crank-pin, w, on the driving-wheel of the sewing-machine. The lever H is comparatively loose 60 on its pivot, and a spiral spring, d, on the portion m of the pin K has a continuous tendency to force the long arm of the lever H outward in the direction of the arrow, Fig. 1, and to press the upper blade of the shears against 65 the fixed blade at and near the point, thereby insuring the efficient shearing action of the two blades.

The cutting-edges of the blades are in such a position in respect to the needle and the 70 needle-hole in the work-plate that as the fabric is being stitched and fed its edges will be properly trimmed, the distance from the stitches to where the trimming takes effect on the fabric being regulated by the adjustment of the 75 plate G on the bed of the machine.

On referring to Figs. 6 and 7 it will be seen that the work-plate S is recessed at v, so as to form a shoulder, y, the lower blade of the shears resting in this recess, and the point of the blade 80 bearing against the shoulder, Fig. 7. This arrangement allows the fabric to pass freely onto the cutting-edge of the lower blade, and permits the formation on this blade of a comparatively blunt point, on which the fabric can- 85 not catch. By this means we are enabled to trim much closer to the seam than can otherwise be done, and the upper blade of the shears is at liberty to pass the lower blade up to the extreme point of the latter without coming 90 into contact with the work-plate. The upper blade should admit of very nice adjustment, so that the shears may exert the proper cutting effect to the extreme point, and this adjustment can be readily effected by shifting 95 the pin K in the slot of the arm H.

We claim as our invention—

1. The combination of the fixed blade of the

shears, the upper blade forming part of the lever H, the sliding block F, adapted to guides in the lever, the vibrating slotted arm M, and the pin K, made adjustable in the said arm 5 and adapted to the sliding block, all substantially as set forth.

2. The combination of the lower fixed blade of the shears with a work-plate, S, having a recess, v, adapted to the said blade and terminating in a shoulder, y, against which the end of the blade abuts, all as set forth.

3. The combination of the lower blade of the shears, having a blunt end, with the work-

plate, having a recess, v, and shoulder y, as set forth.

4. The combination of the work-plate, having a recess, v, and shoulder y, with the lower blade of the shears, having a blunt end and made laterally adjustable, as specified.

In testimony whereof we have signed our names to this specification in the presence of two subscribing witnesses.

ALBIN GARRETT.
RUFUS THOMAS.
